CLAIM

The ornamental design for a controller for smart furniture, as shown and described.

DESCRIPTION

FIG. 1 is a top perspective view of an embodiment of a controller for smart furniture showing my new design;

FIG. 2 is a top plan view thereof;

FIG. 3 is a bottom plan view thereof;

FIG. 4 is a front side view thereof;

FIG. 5 is a left side view thereof; and,

FIG. 6 is a right side view thereof.

The broken lines in FIG. 3 do not form a part of the claimed design.
